SELF-ADJUSTING PIPE WRENCH

Luther Houdesheldt, Garden Grove, Iowa, assignor of one-half to Clair C. Arnold, Garden Grove, Iowa

Application March 10, 1950, Serial No. 148,820

1 Claim. (Cl. 81—126)

1

The present invention relates to a self-adjusting pipe wrench and it consists in the combinations, constructions and arrangements of parts herein described and claimed.

Generally there is provided a self-adjusting pipe wrench having an elongated shank provided with a fixed jaw laterally extending from the outer end thereof, a shaft extending alongside the shank and having a jaw formed in its outer end and which jaw is adapted to cooperate with the fixed jaw. A longitudinal slot is formed in the shank and a block is slidably mounted therein. A spring is also mounted in the slot and is arranged to urge the block in a forward direction. A link interconnects the block with the shaft adjacent the forward end thereof and a bell crank lever forming an operating handle for the device has the outer end of its shorter arm pivotally connected to the rear end of the shaft and has its fulcrum pivotally and adjustably connected with the inner end of the shank.

It is accordingly an object of the invention to provide a self-adjusting pipe wrench of the character set forth.

Another object of the invention is to provide a device of the character set forth which is simple in construction, inexpensive to manufacture and which is effective and efficient in use.

Another object of the invention is the provision in a device of the character set forth of a novel spring-actuated pivot block forming a part of the invention.

A still further object of the invention is the provision in a device of the character set forth of a novel link and lever arrangement for multiplying the pressure ratio between the operating handle and jaws of a wrench.

Other and further objects of the invention will become apparent from a reading of the following specification taken in conjunction with the drawing, in which:

Figure 1 is a side elevational view of an embodiment of the invention with an operating handle forming a part of the invention removed therefrom.

Figure 2 is a view similar to Figure 1 but showing the operating handle attached.

Figure 3 is a view similar to Figures 1 and 2 but showing the operating handle attached to the device in another manner.

Figure 4 is a fragmentary elevational view of Figure 1.

Figure 5 is a sectional view taken along line 5—5 of Figure 1, and

2

Figure 6 is a fragmentary sectional view taken along line 6—6 of Figure 3.

Referring more particularly to the drawing, there is shown therein a self-adjusting pipe wrench provided with an elongated shank 10 having an integrally formed laterally extending fixed jaw 11 at its outer end and provided centrally with a longitudinally extending slot 12 having opposed trackways 13 upon which is slidably arranged a pivot block 14 which is urged outwardly by means of a compression spring 15 interposed between its inner end and the inner end of the slot 12.

A shaft 16 is arranged alongside the shank 10 and is provided with a jaw 17 at its outer end which jaw is provided with a serrated face 18 which is positioned opposite the jaw 11 which is likewise provided with a serrated face 19.

A pair of links 20 is arranged one upon either side of the shank 10 and shaft 16 and are connected by means of a bolt 21 provided with a nut 22 to the pivot block 14 at one of their ends and by means of a rivet 23 to the shaft 16 immediately rearwardly of the jaw 17.

25 A bell crank lever, generally indicated at 24, is provided with a relatively short arm 25 and a relatively long arm 26. An opening 27 is provided in the bell crank 24 adjacent the outer end of the shorter arm 25 and an opening 28 is provided in the bell crank at its fulcrum point. The inner end of the shank 10 is provided with a plurality of openings 29 and the inner end of the shaft 16 is provided with an opening 30.

30 In operation, it will be apparent that the device may be utilized without the use of the bell crank lever 24 and shown in Figure 1 wherein the jaws 11 and 17 may grip a pipe 31 by placing the serrated faces 19 and 18, respectively, thereagainst. It will be understood that the spring 15 will urge the pivot block in an outward direction, that is to say in a direction toward the fixed jaw 11, and that thereafter the shaft 16 may be moved downwardly, as viewed in Figure 1, to thereby further grip the sides of the pipe 45 and to turn the same.

When it is desired to provide additional leverage, the bell crank lever may be arranged in the manner shown in Figure 2 wherein the opening 27 in the shorter arm 25 may be pivotally connected with any one of the openings 29 by means of a bolt or the like and the fulcrum opening 28 connected with the shank 16 through the opening 30 by like means. In this case it will be readily apparent that a downward movement 55 of the longer arm 26 will cause much greater

power to be applied to the pipe because of the ratio in length between the arms 26 and 25.

Likewise it will be apparent that the bell crank may be utilized in the manner shown in Figure 3 wherein the shaft 16 is connected with the outer end of the arm 25 by extending a bolt or the like through the openings 27 and 30 and extending a bolt or the like through the fulcrum opening 28 and a selected opening 29 in the shank 10. Here too a downward movement of the arm 26 will cause great pressure to be exerted upon the movable jaw 17 in its coacting relation with the fixed jaw 11. It will also be seen that the movable jaw 17 will always come into immediate contact with the pipe to be turned due to the fact that the pivot block 14 is at all times urged in a direction toward the fixed jaw 11.

While but one form of the invention has been shown and described herein it will be readily apparent to those skilled in the art that many minor modifications may be made without departing from the spirit of the invention or the scope of the appended claim.

What is claimed is:

A device of the character described comprising an elongated shank having a longitudinal slot therein, a fixed jaw laterally extending from the forward end of said shank, a shaft arranged at one side of said shank in parallel relation thereto, a jaw formed on the forward end of said shaft in opposed relation to the fixed jaw, a pivot block 25 30 35 slidable in the slot, a compression spring inter-

posed between the block and the rear end of the slot, a pair of opposed links having spaced pivots interconnecting the block and the shaft at a point adjacent the jaw end of the shaft, and a bell crank lever having a relatively long handle portion and a relatively short arm, said short arm having spaced pivots pivotally interconnecting the rear ends of said shaft and shank, said slot having a pair of opposed trackways and said block having grooves for receiving said trackways, and said short arm having its pivotal points at substantially the same distance apart as the distance between the pivotal points of said links.

LUTHER HOUDESHELDT.
